D25-53. OR D16,215 EX

DESIGN.

—o—
J. PIRKL.

WINDOW GUARD.

No. 16,215.

Patented Aug. 25, 1885.

UNITED STATES PATENT OFFICE.

JOHN PIRKL, OF BROOKLYN, NEW YORK.

DESIGN FOR A WINDOW-GUARD.

SPECIFICATION forming part of Design No. 16,215, dated August 25, 1885.

Application filed June 26, 1885. Term of patent 7 years.

To all whom it may concern:

Be it known that I, JOHN PIRKL, of Brooklyn, in the county of Kings and State of New York, have originated and invented a new and useful Design for Window-Guards; and I do hereby declare that the following is a full, clear, and exact description thereof, reference being had to the accompanying photograph, forming a part of this specification.

10 The present invention has for its object to provide an ornamental design for window-guards, which is also applicable to wire gates or fencing; and it consists, essentially, of an outer frame, a row of scrolls, each surrounded by a circle, and a row of tapering loops upon each side thereof, substantially as shown in the accompanying photograph, and hereinafter described and claimed.

15 The photograph forming a part of this specification represents a front elevation of a window-guard, which consists of an outer frame, A, of rectangular shape, inclosing the ornamental portions of the device, which consists of the following features: At the center or midway of the ends of the frame A is a row of scrolls, a, surrounded each by a circle, b, and upon each side of the row of scrolls is a row of tapering loops, B, the loops gradually increasing in width as they approach the ends 20 of the frame. Upon the outer or larger ends of the loops B, at one end only of the frame A, are tapering loops C, their smaller ends joining the larger ends of the loops B. The

larger ends of the loops C join the frame A at its end and terminate in scrolls c, located 35 within the loops. The opposite row of loops, B, join with angular loops D, which in turn are joined to the end of the frame A. At a point where the loops B C and B D join there are located between them webs d, which are 40 made by the wire being bent upon itself, each complete circle b, loops B and C D being formed of two pieces of wire, preferably flat in shape, fastened together upon each side of the circle, 45 at the webs d, and to the ends of the frame A.

Having now fully described my invention, what I claim as new, and desire to secure by Letters Patent, is—

1. A design for a window-guard, consisting of an outer frame, a central row of scrolls, 50 each surrounded by a circle, and a row of tapering loops arranged upon each side of the row of scrolls, substantially as shown and described.

2. In a design for a window-guard, a central 55 row of scrolls, each surrounded by a circle, and a row of tapering loops upon each side thereof terminating at their outer ends in loops, one row of which terminate in scrolls, as shown.

In testimony that I claim the foregoing as 60 my own I affix my signature in presence of two witnesses.

JOHN PIRKL.
